GOLF CLUB HEAD

Toney Penna, Jupiter, Fla., assignor to MacGregor Sport Products, Inc., Cincinnati, Ohio, a corporation of Ohio

Filed Mar. 7, 1960, Ser. No. 59,653

Term of patent 3½ years

(Cl. D34—5)

I claim:

The ornamental design for a golf club head, substantially as shown and described.
